DESIGN.

A. T. WILLIS.

RATTLE.

APPLICATION FILED MAY 26, 1920.

56,487.

Patented Oct. 26, 1920.

Albert J. Willis ^{Inventor}
By his Attorney
Werner Block

UNITED STATES PATENT OFFICE.

ALBERT T. WILLIS, OF EAST STROUDSBURG, PENNSYLVANIA, ASSIGNOR TO EXELOID COMPANY OF PENNSYLVANIA, OF EAST STROUDSBURG, PENNSYLVANIA, A CORPORATION OF PENNSYLVANIA.

DESIGN FOR A RATTLE.

56,487.

Specification for Design.

Patented Oct. 26, 1920.

Application filed May 26, 1920. Serial No. 384,475. Term of patent 7 years.

To all whom it may concern:

Be it known that I, ALBERT T. WILLIS, a citizen of the United States of America, residing at East Stroudsburg, Monroe county, State of Pennsylvania, have invented a new, original, and ornamental Design for a Rattle, of which the following is a specification, reference being had to the accompanying drawing, forming part hereof, which represents a perspective view of a rattle embodying my new design.

I claim:

The ornamental design for a rattle, as shown.

Signed at East Stroudsburg, Pennsylvania, this 15 day of May, 1920.

ALBERT T. WILLIS.

Witness:

HARRY M. ALBERT.
